BELL

David W. Osborne, 163 Columbia Ave., Elmhurst, Ill.

Filed July 29, 1963, Ser. No. 76,000

Term of patent 14 years

(Cl. D72—1)

figure 1

FIGURE 1 is a top plan view of the bell embodying my new design.

The bottom of the bell is open and the inside thereof follows the outer contour.

I claim:

The ornamental design for a bell, as shown and described.
